burgh, Pa., a corporation of Pennsylvania

Application September 19, 1944, Serial No. 554,783

6 Claims. (Cl. 315—274)

1

This invention relates to an electric discharge valve of the arc-like type and has particular relation to control apparatus for rendering the valve conductive.

Electric discharge valves of the arc-like type, such as thyratrons, include an anode, cathode and a control electrode. It is a well known characteristic of such valves that they remain non-conductive as long as the control electrode-to-cathode voltage is less positive than a predetermined critical voltage. If an anode-to-cathode voltage exists which is greater than the breakdown voltage of the valve, with the anode positive, the valve becomes conductive the instant the control electrode-to-cathode voltage becomes more positive than the critical voltage. The control electrode then loses control of the valve which continues to conduct until the anode-to-cathode voltage is reduced below the arc drop of the valve. This feature is employed widely where it is desired to render the valve conductive at a predetermined instant. Often an alternating potential or other potential having a steep wave front is impressed between the control electrode and cathode so that the instant at which the control electrode becomes more positive with respect to the cathode than the critical voltage may be accurately predetermined. A peaking transformer energized from an alternating potential source is frequently used for this purpose.

Such arrangements ordinarily operate quite satisfactorily. However, under certain conditions serious difficulties are encountered. In a number of cases it is desirable to render a valve conductive at the instant that some other operation takes place, for example, when a relay is operated. Under such circumstances, it has been customary to provide a voltage which is applicable to the control electrode and cathode upon the closure of the relay contacts. Frequently a pre-charged capacitor is discharged through a discharge circuit including the primary of a peaking transformer when relay contacts in the discharge circuit are closed, the secondary winding of the peaking transformer being connected in circuit between the control electrode and cathode of the valve. However, it has been found that such an arrangement is unreliable in that it occasionally fails to render the valve conductive at the instant desired.

It is accordingly an object of my invention to provide a novel control arrangement for an electric discharge valve of the arc-like type for rendering the valve conductive at a desired instant.

Another object of my invention is to provide a

2

novel control arrangement for rendering an electric discharge valve of the arc-like type conductive at a desired instant, which arrangement is highly reliable in operation.

A further object of my invention is to provide a new and improved control arrangement for rendering an electric discharge valve of the arc-like type conductive at an instant determined by the operation of a relay.

10 My invention arises from the realization that the occasional failures in previous systems as described was caused by the bouncing of the contacts of the relay. The contacts of most relays other than very special expensive relays, bounce upon closing. This bouncing causes a discontinuity in the voltage impulse which is applied between the control electrode and cathode of the valve in the prior arrangements. If the relay contacts bounce at the right moment, the peak portion of the voltage impulse may be missed completely, so that the valve is not rendered conductive.

15 In accordance with my invention, a biasing potential is impressed between the control electrode and cathode of the valve tending to maintain the former less positive with respect to the latter than the critical voltage of the valve. An energy storage device is connected in parallel circuit relation with an impedance, such as a resistor, and the parallel storage device and impedance are connected in a series circuit with a normally closed switch which may be the contacts of a relay. A direct current is then supplied through the series circuit and serves to store up energy in said storage device. When the switch is thereafter opened, the energy so stored is released to effect current flow through the impedance. Means are provided to make the control electrode more positive with respect to the cathode than the critical voltage and thereby render the valve conductive in response to the release of the energy. Since the valve becomes conductive upon the opening of the switch, the bouncing of the contacts if the switch is formed by the contacts of a relay obviously does not affect the instant of firing of the valve.

20 The novel features which I consider characteristic of my invention are set forth with greater particularity in the accompanying claims. The invention itself, however, both as to the organization and method of operation, together with additional objects and advantages, may be best understood from the following description of a specific embodiment when read in connection with the accompanying drawing in which the

single figure is a circuit diagram of an embodiment of my invention.

As shown in the drawing, an electric discharge valve 3 of the arc-like type, preferably a thyratron, has its anode 5 and cathode 7 connected in a circuit extending from the anode through a normally closed push button switch 9, a load 11 and a source of potential such as a battery 13 to the cathode. The battery 13 produces a voltage between the anode 5 and the cathode 7 which is greater than the breakdown voltage of the valve, with the anode 5 being positive.

The control electrode or grid 15 of the valve 3 is connected to the cathode 7 in a circuit which extends from the grid through a grid resistor 17, the secondary winding 19 of a transformer 21, and a source of biasing potential such as a battery 23 to the cathode. In addition a loading resistor 25 is connected in shunt across the secondary winding 19. The battery 23 tends to maintain the grid 15 less positive with respect to the cathode 7 than the critical voltage of the valve, and thus maintain the valve non-conductive.

The primary winding 27 of the transformer 21 is connected across a source of direct-current potential 29 through an adjustable resistor 31 and the normally closed contacts 33 of a relay 35. Another resistor 34 is connected in shunt across the primary winding 27.

The source of direct-current potential 29 is illustrated as a resistor which is supplied from alternating potential supply lines 36 and 37 through a transformer 39, a full wave rectifier 41 and a filtering capacitor 43. Any other source of direct-current potential of the proper magnitude and polarity may, of course, be used.

The contacts 33 of the relay 35 may be opened by energization of the relay coil 45. This coil is illustrated as connected in circuit with a normally open push-button switch 47 across the alternating potential supply lines 36 and 37.

While the relay contacts 33 are closed, direct current flows from the source 29 through the contacts 33, adjustable resistor 31, and the parallel-connected primary winding 27 and resistor 34. Since the impedance of the resistor 34 is high compared to the impedance of the primary winding 27, most of the current flows through the primary winding and stores up energy in the transformer. If push-button switch 47 is then closed, relay coil 45 is energized and contacts 33 are opened. As a result, the supply of direct current is interrupted and the energy stored in the transformer is released. Some of the energy so released tends to keep the current flowing through the primary winding 27 in the same direction as the current previously supplied from the source 29 because of the inductive effect of the primary winding. Consequently, current flows in the circuit made up of the primary winding 27 and the resistor 34.

The rapid change of flux in the transformer caused by the release of energy stored therein produces a voltage impulse across the secondary winding 19 which is of such polarity and magnitude as to overcome the biasing potential of the battery 23 and render the valve 3 conductive. The magnitude of the voltage impulse may be determined by the size of the resistor 34.

After the valve is conductive the push-button switch 47 may be released to effect reclosure of contacts 33. The valve 3 then continues to conduct current until the push-button switch 9 is opened. With the opening of the push-button switch 9 the anode-to-cathode voltage drops to

zero and the valve 3 becomes nonconductive. If the push-button switch 9 is then allowed to reclose, the valve may be rendered conductive again by reclosure of the push-button switch 47.

The purpose of the adjustable resistor 31 in circuit with the primary winding 27 is to limit the magnitude of the direct current supplied through the primary winding to the value permissible with the particular transformer employed. It is therefore understandable that the right end of resistor 34 may be connected to any point along the circuit between the contacts 33 and the right-hand end of primary winding 27 without changing the operation of the circuit if the value of the resistor is selected properly in accordance with the point of connection.

It is also to be understood that while switches 9 and 47 are shown as push-button switches, various other well known means may be employed to effect energization and deenergization of the corresponding circuits. Contacts 33 may also be replaced with other switch means if desired, the valve being rendered conductive upon the opening of such other switch means. It is also to be noted that an alternating potential may be employed in the anode circuit of the valve in place of the battery 13. Under such circumstances energization of the relay 35 should be co-ordinated with the alternating potential to occur during the half period in which the anode 5 of the valve is positive.

While I have shown and described a specific embodiment of my invention, I am well aware that many modifications thereof are possible without departing from the spirit of the invention. It is not my intention therefore to limit my invention to the specific embodiment shown.

I claim as my invention:

1. Control apparatus for an electric discharge valve of the arc-like type having an anode, cathode and control electrode, comprising a control circuit connected from said control electrode to said cathode and including biasing potential means tending to maintain the former less positive with respect to the latter than the critical voltage of the valve, an energy storage device, impedance means connected in parallel circuit relation with said device, a normally closed switch connected in a series circuit with said paralleled device and impedance means, and means adapted to supply direct current through said series circuit, whereby energy stored in said device by said direct current is released to effect current flow through said impedance means when said switch is opened, said control circuit being coupled to said device to make said control electrode more positive with respect to said cathode than said critical voltage in response to the release of said energy.

2. Control apparatus for an electric discharge valve of the arc-like type having an anode, cathode and control electrode, comprising a transformer having a primary and a secondary winding, circuit means connecting said secondary winding in a circuit between said control electrode and cathode including biasing potential means tending to maintain the control electrode less positive with respect to the cathode than the critical voltage of said valve, impedance means connected in parallel circuit relation with said primary winding, a normally closed switch connected in a series circuit with said paralleled impedance means and primary winding, and means adapted to supply direct current through said series circuit of such polarity that the release

of energy stored thereby in said transformer, as effected by opening of said switch, causes a voltage impulse across said secondary winding to render said control electrode more positive with respect to the cathode than said critical voltage.

3. Control apparatus for an electric discharge valve of the arc-like type having an anode, cathode and control electrode, comprising a transformer having a primary and a secondary winding, circuit means connecting said secondary winding in a circuit between said control electrode and cathode including biasing potential means tending to maintain the control electrode less positive with respect to the cathode than the critical voltage of said valve, impedance means connected in parallel circuit relation with said primary winding, a relay having normally closed contacts connected in a series circuit with said paralleled impedance means and primary winding, means adapted to supply direct current through said series circuit, and means for operating said relay to open said contacts, the polarity of said direct current being such that the release of energy stored thereby in said transformer, as effected by opening of said contacts, causes a voltage impulse across said secondary winding to render said control electrode more positive with respect to the cathode than said critical voltage.

4. Control apparatus for an electric discharge valve of the arc-like type having an anode, cathode and control electrode, comprising a transformer having a primary and a secondary winding, circuit means connecting said secondary winding in a circuit between said control electrode and cathode including biasing potential means tending to maintain the control electrode less positive with respect to the cathode than the critical voltage of said valve, a resistor connected in parallel circuit relation with said primary winding, a normally closed switch connected in a series circuit with said paralleled resistor and primary winding, and means adapted to supply direct current through said series circuit of such polarity that the release of energy stored thereby in said transformer, as effected by opening of said switch, causes a voltage impulse across said secondary winding to render said control electrode more positive with respect to the cathode than said critical voltage.

5. A control system comprising an electric discharge valve of the arc-like type having an anode, cathode and control electrode, means for impressing a positive voltage between said anode and cathode, a control circuit connected from said control electrode to said cathode and including biasing potential means tending to maintain the former less positive with respect to the latter than the critical voltage of the valve, an energy storage device, impedance means connected in parallel circuit relation with said device, a normally closed switch connected in a series circuit with said paralleled device and impedance means, and means adapted to supply direct current through said series circuit, whereby energy stored in said device by said direct current may be released to effect current flow through said impedance means when said switch is opened, said control circuit being coupled to said device to make said control electrode more positive with respect to said cathode than said critical voltage in response to the release of said energy whereby said valve is rendered conductive when said switch is opened.

6. A control system comprising an electric discharge valve of the arc-like type having an anode, cathode and control electrode, means for impressing a positive voltage across said anode and cathode, a transformer having a primary and a secondary winding, circuit means connecting said secondary winding in a circuit between said control electrode and cathode including biasing potential means tending to maintain the control electrode less positive with respect to the cathode than the critical voltage of said valve, a resistor connected in parallel circuit relation with said primary winding, a normally closed switch connected in a series circuit with said paralleled impedance means and primary winding, and means adapted to supply direct current through said series circuit of such polarity that the release of energy stored thereby in said transformer, as effected by opening of said switch, causes a voltage impulse across said secondary winding to render said control electrode more positive with respect to the cathode than said critical voltage whereby said valve is rendered conductive when said switch is opened.
